No. 689,213.

Patented Dec. 17, 1901.

M. F. NICHOLSON.

PIE RACK.

(Application filed July 10, 1901.

(No Model.)

UNITED STATES PATENT OFFICE.

MILLARD F. NICHOLSON, OF WASHINGTON, DISTRICT OF COLUMBIA.

PIE-RACK.

SPECIFICATION forming part of Letters Patent No. 689,213, dated December 17, 1901.

Application filed July 10, 1901. Serial No. 67,756. (No model.)

To all whom it may concern:

Be it known that I, MILLARD F. NICHOLSON, a citizen of the United States, residing at Washington, in the District of Columbia, have 5 invented certain new and useful Improvements in Pie-Racks; and I do hereby declare the following to be a full, clear, and exact description of the invention, such as will enable others skilled in the art to which it appertains to make and use the same.

My invention relates to pie-racks; and it consists generally in the novel construction and arrangement of the several parts, as will be hereinafter more fully described, and 15 briefly stated in the claims.

The principal object of the invention is to produce a pie-rack of the simplest and cheapest form consistent with strength and durability.

20 Another object of the invention is to increase the holding capacity of the rack without increasing its size or dimensions to any appreciable extent.

These and other objects are attained by 25 means of the device illustrated in the accompanying drawings, in which—

Figure 1 is a perspective view of my improved pie-rack complete, with a portion of the screen-door broken away to show the revoluble part of the rack. Fig. 2 is a horizontal section. Fig. 3 is a central vertical section, and Fig. 4 is a modified form of holder.

Referring to the several views, the letter A indicates a suitable case, in which the revoluble holder B is journaled. The case is composed of the bottom and top pieces a' and stiles a^2 , put together in any well-known manner, preferably by screws. Three sides of the case are preferably provided with glass panels, the side edges of the stiles being grooved to receive them, and the other or rear side is preferably provided with screen-doors a^3 a^4 .

The holder B is composed of the bottom and top plates b b' of any suitable shape, preferably round, outer posts or stiles b^2 , and central post or stile b^3 , put together in any suitable manner. The outer posts are preferably of right-angle shape in cross-section, with the outer edge of each arm or rib of the angle provided with notched or grooved pie-plate seats b^4 , while the central post is preferably octagon shape in cross-section, as clearly shown

in Fig. 2, and has four of its sides provided with notched or grooved seats b^5 —double the number of those on the posts—so that seats 55 will be provided for tiers of pies on all four sides.

Secured to the top and bottom pieces of the holder B are plates C, having pintles c, which pintles are received in sockets d of the plates 60 D, secured to the top and bottom of the case.

In order to provide for the quick escape of heat arising from the pies when placed in the rack, I form suitable vents E in the tops of both the case and pie-holder and suitable air-inlets in the bottom rails of the glass sides. The screen-door and these vents provide ample ventilation, thereby preventing the pies becoming moldy.

The peculiar construction of the holder permits a larger number of pies being contained therein than the ordinary holders now in use, as the seats are so arranged that the pies are placed in tiers, with the pies in one tier overlapping those in the adjacent tier, as shown 75 in Fig. 2. This is one of the important advantages of my invention, especially where economy in space is desired. The simplicity of structure insures cleanliness and also facility in placing and replacing the pies. 80

The modification shown in Fig. 4 is adapted for large and small pies, the holder in this instance being composed of three plates—a top plate b^6 , a bottom plate b^7 , and an intervening plate b^8 . That part of the holder between 85 the top and intervening plates is similar in construction to the holder B; but that part between the intervening and bottom plates is of slightly different construction, there being but three of the pie-plate seat-posts, instead 90 of four, employed and only three notched or recessed sides on the central post. This construction of holder is particularly desirable for small dealers; but for large dealers I prefer to make a rack for each size of pies. 95

Both the case and holder may be constructed of any suitable material, and the pie-seats may be of any desired shape suitable to receive the edge of the pie-plate. Various other modifications or changes may be made without departing from the spirit of my invention or sacrificing the principle thereof—such, for instance, as making the outer posts of the holder triangular in cross-section, with the

pie-plate seats in the adjacent corners thereof, and making the central post square, with the said seats arranged in its corners, or cross shape in cross-section and arranging the pie-plate seats in the outer edges of the ribs or wings.

Having thus fully described my invention, what I claim is—

1. A pie-rack composed of a suitable base, and a revoluble holder having outer posts provided with staggered seats, and a central post provided with seats to correspond therewith, whereby pies may be arranged in overlapped position.
- 15 2. In a pie-rack, the combination with a

suitable support, of a holder composed of top and bottom plates, and an intervening plate mounted on a central post, four posts between the top and intervening plates, and three posts between the intervening and bottom plates, and seats on the outer and central posts, so arranged as to hold the pies in overlapped position.

In testimony whereof I affix my signature in the presence of two witnesses.

MILLARD F. NICHOLSON.
